UNITED STATES PATENT OFFICE.

CLEON H. TONDEUR, OF CANASTOTA, NEW YORK.

APPARATUS FOR VAPORIZING AND BURNING FUEL-OIL FOR STEAM-BOILERS.

1,366,976.

Specification of Letters Patent.

Patented Feb. 1, 1921.

Application filed February 14, 1920. Serial No. 358,752.

To all whom it may concern:

Be it known that I, CLEON H. TONDEUR, of Canastota, in the county of Madison, in the State of New York, have invented new and useful Improvements in Apparatus for Vaporizing and Burning Fuel-Oil for Steam-Boilers, of which the following, taken in connection with the accompanying drawings, is a full, clear, and exact description.

10 This invention relates to certain improvements in apparatus for burning crude oil as a fuel for steam boilers and analogous uses, and refers more particularly to the construction of the oil burner and to the means 15 for supplying heated air thereto for supporting the combustion of the fuel as it emerges from the burner into the combustion chamber.

The main object is to provide a simple, 20 practical and efficient means for more effectively vaporizing the oil upon its exit from the burner into the combustion chamber and, at the same time, to maintain a sufficient supply of heated air under pressure to consume 25 practically the entire fuel vapor and resultant gases, not only for economical purposes, but to reduce to a minimum the escape of combustible products to the atmosphere.

30 Another object is to cause the air to flow through tortuous closed conduits within the combustion chamber, and in a general direction opposite to that in which the vaporized fuel is projected for the purpose of heating 35 the air to a high degree in transit to the burner.

Other objects and uses relating to specific parts of the apparatus will be brought out in the following description:

40 In the drawings:

Figure 1 is a longitudinal vertical sectional view of a steam boiler housing showing in elevation a steam boiler and my improved fuel vaporizer and burner in operative position.

45 Fig. 2 is a horizontal sectional view of the same housing in a plane beneath the boiler or just above the burners and air supply pipes, which latter are shown in top plan, except that the oil supply pipes are shown in section.

50 Fig. 3 is an enlarged vertical sectional view of one of the burners and adjacent portion of the front wall of the boiler housing, 55 the major portion of the air conduit being broken away.

As illustrated, the fuel vaporizing and burning apparatus is mounted mainly within or upon the housing or casing —1— of a horizontal return flue steam boiler —2— 60 and comprises a spray nozzle —3—, a mixing chamber —4— and an air supply pipe —5—.

The housing —1— is provided with a combustion chamber —6— underlying the 65 boiler —2— and communicating with the rear ends of the flues of the boiler to allow the unburned products of combustion to pass through said flues to a smoke flue —7— at the front of the boiler, the boiler casing 70 or housing —1— being also provided with the usual baffle plate —8 and 9— to cut off direct communication with the combustion chamber —6— and flue —7—, and to cause escaping products of combustion to pass 75 from front to rear and to return through the flues of the boiler to the stack or flue —7.

I preferably employed a plurality of, in this instance, three burners including the nozzles —3—, mixing chambers —4— and 80 air supply pipes —5—, arranged side by side lengthwise of the boiler and extending into the combustion chamber —6—, each nozzle —3— being extended through a suitable opening 3' in the front wall of the casing —1— directly beneath the baffle plate 85 —8—.

The outer end of each nozzle is provided with an inlet —10— connected to an oil-fuel supply pipe —11— having a valve —12— 90 for controlling the supply of oil to the nozzle, the inner end of said nozzle being provided with a restricted outlet —13— which is controlled by a needle valve —14—, the latter being extended centrally through a 95 suitable gland —15— in the outer end of a nozzle, and is provided with a hand piece —16— by which it may be adjusted to regulate the flow of the oil through the outlet —13, the stem of the valve being provided 100 with a screw thereto —17— engaging a threaded aperture in the gland —15— to permit desired adjustment of the valve by reduction thereof.

The mixing chamber —4— is located 105 within the combustion chamber —6— adjacent the front wall of the casing —1— and preferably consists of a shell of suitable material having a threaded aperture —18— in its outer end in which the inner end of 110 the nozzle —3— is secured, said mixing chamber being also provided with an addi-

tional aperture 18' for receiving the adjacent end of the air pipe —5.

A perforated plate or screen —19— is secured across the inner end of the mixing chamber —4— to facilitate the disintegration and vaporizing of the fuel which may be projected into the said mixing chamber through the valve outlet —13— of the nozzle —3—, and also to permit the exit of the mixed vaporized fuel and air into the combustion chamber —6— where the mixture is burned for converting the water in the boiler to steam, and also for heating the air in the pipe —5.

15 The air pipes —5— extend centrally through the combustion chamber from front to rear, and through the front and rear walls of the casing —1—, the front end of each pipe being provided with a return bend 20 —20, which is located just in front of the front wall of the housing —1— and is connected by a return branch —5'— of the mixing chamber —4— through the opening 18' or just below and in close proximity to the 25 inner discharge end of the nozzle —3—.

The perforated plate —19— is disposed a short distance from the delivery end of the nozzle —3— and serves as a baffle plate to spread and pulverize the oil and to assist 30 the valve nozzle —13— in vaporizing said oil and causing it to mix thoroughly with the air before being discharged into the combustion chamber.

The inner end of the nozzle —3— projects 35 slightly beyond the inner end of the branch air pipe 5' so that the heated air which is introduced into the mixing chamber under pressure may assist in drawing the fuel from the mouth of the nozzle into said mixing 40 chamber, which is of relatively large area, as compared with that of the nozzle —3— and air inlet, to allow the fuel and air to become thoroughly mixed before passing through the perforations of the plate —19.

45 The intermediate portion of the air pipe —5— extending through a bridge wall —21— beyond casing —1— and the portion thereof between said bridge wall and rear wall of the casing is tortuous by vertical 50 corrugations —22—, thereby greatly increasing the area of the conduit exposed to the heated products of combustion as they are deflected downwardly over the bridge wall —21— in transit to the rear ends of 55 the valves at the boiler —2—, thereby causing the air to enter the mixing chamber at a sufficiently high degree of heat to expedite the vaporization of the fuel immediately upon its entrance into the mixing chamber 60 through the nozzle —3—.

A valve or damper —23— is placed within the return bend —20— of the air pipe —5— and is adjusted at will to regulate the volume of heated air entering the mixing 65 chamber —4—.

If desired, the atmospheric air may be fed through the several pipes —5— under pressure, and, for this purpose, their rear ends are connected to a suitable blower —24— which may be driven by any available source of power not shown.

I have shown each of the nozzles —3— provided with a separate oil supply pipe —11— but it is evident that they may be connected to a single supply pipe leading 75 from a main reservoir not shown, in which case, each of the pipes —11— would become a branch pipe and the passage of the oil therethrough would be controlled by the valve —12—, while the passage of the oil 80 from the nozzle would be controlled by the valve —14—, which, together with the air valve —23—, enables the operator to regulate the flow of both oil and air to produce the desired mixture in the chamber —4—, which 85 mixture then passes through the perforated plate —19— and is ignited and burns in the combustion chamber —6— to convert water in the boiler —2— to steam, and, at the same time, to heat the air passing through the 90 pipe —5— and its corrugations —22—.

What I claim is:

1. The combination with a return flue boiler and a combustion chamber underlying the boiler, a mixing chamber within the combustion chamber and provided with a fuel inlet and an air inlet, and also provided with a perforated wall forming an outlet, a nozzle connected to the fuel outlet and provided with a valve for regulating the passage of 100 fuel into the mixing chamber, a fuel supply pipe connected to the nozzle and provided with a fuel regulating valve, an air pipe extending entirely through the combustion chamber from front to rear and having its 105 front end connected to the air inlet of the mixing chamber and its other end communicating with the atmosphere.

2. The combination with a return flue boiler and a combustion chamber underlying 110 the boiler, a mixing chamber within the combustion chamber and provided with a fuel inlet and an air inlet, and also provided with a perforated wall forming an outlet, a nozzle connected to the fuel outlet and provided with a valve for regulating the passage of fuel into the mixing chamber, a fuel supply pipe connected to the nozzle and provided with a fuel regulating valve, an air pipe extending entirely through the combustion chamber from front to rear and having its 115 front end connected to the air inlet of the mixing chamber and its other end communicating with the atmosphere, said air pipe having portions thereof within the 120 combustion chamber corrugated for exposing a greater area thereof to the heated products of combustion.

3. The combination with a return flue boiler and a combustion chamber underlying 130

the boiler, a mixing chamber within the combustion chamber and provided with a fuel inlet and an air inlet, and also provided with a perforated wall forming an outlet, a nozzle connected to the fuel outlet and provided with a valve for regulating the passage of fuel into the mixing chamber, a fuel supply pipe connected to the nozzle and provided with a fuel regulating valve, an 10 air pipe extending entirely through the combustion chamber from front to rear and having its front end connected to the air inlet of the mixing chamber and its other end communicating with the atmosphere, and a 15 blower connected to the rear end of the air pipe for forcing air therethrough.

4. The combination with a return flue boiler, a housing for the boiler having a combustion chamber and a bridge wall intermediate the ends of said chamber, a mixing chamber in the combustion chamber in front of the bridge wall and below the boiler and provided with a fuel inlet and an air

inlet in its front end and having a perforated wall in its rear end for permitting the 25 discharge of the fuel mixture into the combustion chamber, a nozzle connected to the fuel inlet of the mixing chamber and provided with a valve for controlling the supply of fuel to said mixing chamber, an oil 30 supply pipe connected to the nozzle, an air pipe extending entirely through the combustion chamber from front to rear and having its front end connected to the air inlet to the mixing chamber, the portion of said air 35 pipe between the bridge wall and rear wall of the housing being corrugated vertically, and means for forcing air through the air pipe.

In witness whereof I have hereunto set my 40 hand this 2nd day of February, 1920.

CLEON H. TONDEUR.
